(57) **CLAIM**

The ornamental design for a tofu press, as shown and described.

DESCRIPTION

FIG. 1 is a top, front, left side perspective exploded view of a tofu press;

FIG. 2 is a top, front, left side perspective view of a press plate assembly of the tofu press;

FIG. 3 is a rear elevation view of the press plate assembly of FIG. 2;

FIG. 4 is a front elevation view of the press plate assembly of FIG. 2;

FIG. 5 is a right side elevation view of the press plate assembly of FIG. 2;

FIG. 6 is a left side elevation view of the press plate assembly of FIG. 2;

FIG. 7 is a top plan view of the press plate assembly of FIG. 2;

FIG. 8 is a bottom plan view of the press plate assembly of FIG. 2;

FIG. 9 is a top, front, left side perspective view of a cutting blade assembly of the tofu press;

FIG. 10 is a front elevation view of the cutting blade assembly of FIG. 9, a rear elevation view being a mirror image thereof;

FIG. 11 is a right side elevation view of the cutting blade assembly of FIG. 9, a left side elevation view being a mirror image thereof;

FIG. 12 is a top plan view of the cutting blade assembly of FIG. 9;

FIG. 13 is a bottom plan view of the cutting blade assembly of FIG. 9;

FIG. 14 is a top, front, left side perspective view of a base plate of the tofu press;

FIG. 15 is a front elevation view of the base plate of FIG. 14, a rear elevation view being a mirror image thereof;

FIG. 16 is a right side elevation view of the base plate of FIG. 14, a left side elevation view being a mirror image thereof;

(Continued)

FIG. 17 is a bottom plan view of the base plate of FIG. 14;
 FIG. 18 is a top plan view of the base plate of FIG. 14;
 FIG. 19 is a top, front, left side perspective view of a container of the tofu press;
 FIG. 20 is a front elevation view of the container of FIG. 19, a rear elevation view being a mirror image thereof;
 FIG. 21 is a right side elevation view of the container of FIG. 19;
 FIG. 22 is a left side elevation view of the container of FIG. 19;
 FIG. 23 is a top plan view of the container of FIG. 19;
 FIG. 24 is a bottom plan view of the container of FIG. 19;
 FIG. 25 is a top, front, left side perspective view of the tofu press in its assembled state;
 FIG. 26 is a front elevation view of the tofu press in its assembled state;
 FIG. 27 is a rear elevation view of the tofu press in its assembled state;
 FIG. 28 is a right side elevation view of the tofu press in its assembled state;
 FIG. 29 is a left side elevation view of the tofu press in its assembled state;
 FIG. 30 is a top plan view of the tofu press in its assembled state; and,
 FIG. 31 is a bottom plan view of the tofu press in its assembled state.
 All broken lines illustrate portions of the tofu press that form no part of the claimed design.

1 Claim, 18 Drawing Sheets
